UNITED STATES PATENT OFFICE.

WALTER C. HUTH, OF NEW HAVEN, CONNECTICUT, ASSIGNOR TO THE CRAWFORD OVEN CO., OF NEW HAVEN, CONNECTICUT, A CORPORATION.

AUTOMATIC SAFETY-LOADING MECHANISM FOR OVENS.

Application filed December 28, 1927. Serial No. 243,080.

My invention relates to improved automatic safety loading mechanisms designed with particular reference for use in conjunction with baking-ovens of the conveyor or moving-hearth type, the object being to produce a reliable loading mechanism constructed with particular reference to saving time and insuring a high degree of regularity in the placement or delivery of the articles being handled upon the moving hearth.

With these ends in view, my invention consists in an automatic safety loading mechanism characterized by a construction and arrangement of parts, wherein the resistance to the delivery movement of a pusher-bar automatically stops the timer thereof, whereby the pusher-bar, when such resistance is relieved, is caused to resume and complete its interrupted delivery movement.

My invention further consists in an automatic safety loading mechanism for ovens characterized as above and having certain details of construction and combinations of parts as will be hereinafter described and pointed out in the claims.

In the accompanying drawings:

Fig. 1 is a view in end elevation of an oven equipped with my improved automatic safety loading mechanism;

Fig. 2 is a broken side view thereof;

Fig. 3 is a broken top or plan view thereof;

Fig. 4 is an enlarged view in vertical longitudinal section of one of the telescoping thrust-links of my improved mechanism, showing, also, the pusher-bar, loading-table, and one of the swinging operating-arms of the mechanism;

Fig. 5 is a corresponding view, showing the parts in the positions due to them when an obstruction prevents the advance of the pusher-bar; and

Fig. 6 is a plan view of one of the two switches with its cover removed, also showing schematically the complementary switch, the motor, and the circuit in which both of these switches are interposed.

In carrying out my invention, as herein shown, I provide a pusher-bar 10, consisting of an angle iron moving in the horizontal plane and provided, near its ends, with brackets 11 each mounting a roller 12 traveling upon a track-bar 13 secured to the upper face of the ends of a loading-table or shelf 14, which constitutes the delivery-surface of the oven 15. The inner edge of the said table

projects into the said oven over the upper reach of the conveyor or movable hearth 16, which may be of any approved construction.

Each of the brackets 11 aforesaid is provided with a pair of upstanding arms 17 receiving between them the forward end of the extension-member 18 of a telescoping thrust-link, comprising, also, a tubular-member 19 and a plunger-member 20. The rear end of the said extension-member 18 enters the forward end of the tubular-member 19 in which it is adjustably secured by set-screws 21. The said extension-member 18, which is pivotally secured to the upstanding arms 17 by means of a pin 22, is formed with a deep clearance-bore 23 opening out of its rear end for the clearance of a head 24 at the forward end of a coupling-rod 25, the forward end of which is entered into a bore 26 in the rear end of the said plunger-member and secured in place therein by a pin 27. The rear end of the rod 25 is threaded for the reception of an adjusting-nut 28 for regulating the tension of a helical safety-spring 29 located within the rear end of the tubular-member 19, encircling the rod 25, and interposed between the nut 28 aforesaid and an abutment-ring 31 located within the said tubular-member and secured in place therein by set-screws 32. The forward end of the rod 25 passes through and has bearing in the ring 31, with the forward face of which its head 24 is engaged under normal conditions, as clearly shown in Fig. 4.

The rear end of the plunger-member 20 is entered into the bifurcated lower end of a swinging bowed operating-arm 33 and pivotally connected therewith by a pin 34. The upper end of the said arm is formed with a hub 35 by means of which it is rigidly attached to one end of an oscillating shaft 36, the ends of which bear in journals 37 secured to the frame 38 of my improved loading mechanism. The complementary thrust-link unit is of corresponding construction, and need not, therefore, be specifically described, since one description will answer for both.

About midway of its length, the oscillating shaft 36 has secured to it an upstanding rocker-arm 39 having a slot 40 receiving an adjustable coupling-pin 41 which passes through the rear end of a link 42 formed at its forward end with a fork 43 embracing and guided by a cam-shaft 44, and provided with a pin 45 extending laterally into a groove 46 in one face of a cam 47, which forms the timer

of my improved loading-mechanism for the reason that the shape of its groove 46 determines the nature and the speed of the forward and back strokes of the pusher-bar 10, as well 5 as the intervals between such strokes.

The cam-shaft 44 is connected by means of a universal coupling 48 to the low-speed shaft 49 of a reduction-gear mechanism 50 (of any approved type) having its high-speed shaft 10 51 furnished with a gear 52 meshed into by a pinion 53 on the driving-shaft 54 of a variable speed-transmission 55 of the well-known Reeves type. The drive-shaft 56 of the said variable speed-transmission carries a sprocket-wheel 57 connected by a sprocket-chain 58 with a small sprocket-wheel 59 on the shaft 60 of an electric motor 61.

In the ordinary and expected operation of my improved loading-mechanism, the said 20 motor 61 causes the uniform rotation of the timer-cam 47 and, through the described connections between the same and the push-bar, also causes the regular reciprocation thereof forward and back over the loading-table 14, 25 so as to push pans 62, placed in front of the bar, off upon the upper reach of the conveyor or traveling hearth 16 in regular spaced placement thereupon, whether in contact with each other or not.

30 It frequently happens in the use of baking ovens of the conveyor type that the push-bar delivers bread pans or other articles from the shelf to the conveyor when the same is not ready to receive them, for one reason or another, as, for instance, its tardiness in carrying pans previously delivered upon it forward out of the way, so as to make room for the oncoming pans. Under these and similar circumstances not necessary to rehearse 35 in detail, but well understood by users of such ovens, jams occur, oftentimes resulting in damage to the mechanism or the pans or both and always entailing the loss of valuable time before the jam can be relieved and the trouble removed.

40 To prevent such jams, I provide for stopping the timer-cam by utilizing any untoward resistance to the advance of the push-bar for cutting off the supply of current to the motor, whereby the cam comes to a stop and the forward movement of the pusher-bar is halted.

45 With the above end in view, I mount corresponding switch-mechanisms upon the upper faces of the tubular-members 19 of the two complementary telescoping thrust-links already described. As these switch-mechanisms are identical in construction and operation, a description of one will suffice for both.

50 Each of the said switch-mechanisms consists of a box-like housing 63 receiving a pair of parallel contact-plates 64 spaced apart and mounted upon an insulating-block 65, through which screws 66 pass to attach the switch-unit to the tubular-member 19 afore-

said. The said contact-plates are respectively engaged for normally closing the circuit between them by the respective fingers 67 of a circuit-closing yoke 68 carried by a bell-crank lever 69, from which it is insulated by a fiber-block 70. The said bell-crank lever is hung upon a pin 71 supported in ears 72 offsetting from the rear end of the housing 63. Normally, the fingers 67 are held in contact with the plates 64 by means of a helical spring 73, the respective ends of which are sleeved over studs 74 and 75 respectively formed upon the housing 63 and the lever 69, as shown in Figs. 4 and 5. The contact-plates 64 of the two complementary switches are electrically coupled together in series with each other and with a relay-switch 78 by conductors 76. The relay-switch just mentioned is of ordinary and well-known form and requires no detail illustration or description, other than to say that it is controlled by the current flowing through the conductors 76 and in turn controls the supply of current flowing through the conductor 79 to the motor 61. As shown, a manually-operable switch 80 is also interposed in the circuit of the conductors 76 and in series with the automatic switches. Each of the two plunger-members 20 carries an upstanding safety-pin 77 arranged in position to contact with the bell-crank lever 69 for rocking the same to break the circuit, as will hereinafter appear.

55 In the normal operation of my improved loading-mechanism, the pusher-bar will be moved forward and back by the timer-cam 47 at regular intervals, predicated upon a variety of factors, but chiefly upon the speed of the traveling hearth. When a jam occurs, for whatever reason, the pusher-bar meets with undue resistance to its forward travel. Thereupon the springs 25 of the thrust-links will compress and permit the same to telescope, bringing the safety-pins 77 into contact with the bell-crank switch levers 69, whereby the same will be rocked against the tension of their springs 74 and the contact-yokes 67 lifted away from the contact-plates 64 of the two switches, whereby the circuit to the motor 61 will be broken and the entire loading mechanism stopped, including the cam. This action, while not instantaneous, is so prompt that the forward movement of the pusher-bar is arrested before any damage can result from the jam, whatever its cause.

60 When the resistance to the forward movement of the pusher-bar is eased off, in whatever manner, the springs 29 will reassert themselves and move the tubular-members 19 and the respective switch-units carried thereby forward, whereby the levers 69 of the two switches will be moved out of engagement with the safety-pins 77, thereby permitting the springs 73 to re-close the circuit through

the relay-switch 78, which will at once re-start the motor 61 and hence the loading mechanism, including the timer-cam 47, which will operate to resume, so to speak, its work of reciprocating the pusher-bar as though it had not been interrupted in such work by the jam. In other words, the timer-cam, when started, will move the pusher-bar forward to the limit of its forward stroke and then rearward to the limit of its rearward stroke, as though its normal operation had been uninterrupted.

It will be seen from the foregoing description that, as my improved loading mechanism is constructed and organized, it entirely stops running as a mechanism almost immediately after the occurrence of a jam, on the easing up of which below the power of the springs 29, the same act to close the circuit and re-start the cam and hence the mechanism, whereas, in the mechanisms of the prior art, when the pusher-bar was halted by a jam, the remainder of the mechanism continued to go through its regular cycle of movement, with the result that the pusher-bar was not compelled to resume and complete any given forward stroke when the jam eased off. All that was left to chance, since, in the majority of instances, the bar would, after making a partial forward movement and meeting with a jam, after a short interval retire and start a new forward movement. In other words, in the loading mechanisms of the prior art, the cycles of movement of the pusher-bar were mutilated, so to speak, by the occurrences of jams, whereas, in my improved device, the cycles of movement of the pusher-bar are always complete, though in case of jams, delayed.

By automatically stopping the means employed for reciprocating the pusher-bar itself, the attendant is enabled to do what is necessary to release the jam, unhampered by the reciprocation of the bar, and without the necessity of performing any manual operations for stopping and starting the bar.

Furthermore, inasmuch as the bar is always carried through its stroke, it can never retire and pick up an additional row of pans and jam them up against a partially-delivered preceding row of pans, as will sometimes happen with the devices of the prior art. When the above contingency happens, the initial jam is very much aggravated.

Also, under my improved construction, the skewing of the pans upon the conveyor is avoided and their linear alignment theron preserved, which is a highly important factor in uniform baking.

I claim:

1. The combination with an oven, a movable conveyor located therein, and a delivery-surface positioned adjacent to the conveyor; of a loading-mechanism for delivering articles from the said surface to the conveyor, comprising a reciprocating pusher-bar, a

timer therefor, means for driving the timer, and means controlled by the said bar for automatically stopping and starting the said timer; whereby the pusher-bar is compelled, before it can be retracted, to complete any one of its delivery movements which may have been halted by untoward resistance.

2. The combination with an oven, a movable conveyor located therein, and a delivery-surface positioned adjacent to the conveyor; of a loading-mechanism for delivering the articles from the said surface to the conveyor, comprising a reciprocating pusher-bar, a timer-cam therefor, means for driving the timer-cam, and means controlled by the said bar for automatically stopping and starting the said timer-cam; whereby the pusher-bar is compelled, before it can be retracted, to complete any one of its delivery movements which may have been halted by untoward resistance.

3. The combination with an oven, a movable conveyor located therein, and a delivery-surface positioned adjacent to the conveyor; of a loading-mechanism for delivering articles from the said surface to the conveyor, comprising a reciprocating pusher-bar, a timer therefor, means for driving the said timer, and electrical means brought into operation by variations in the resistance offered by the articles to the delivery movement of the pusher-bar for stopping and starting the said timer; whereby the pusher-bar is compelled, before it can be retracted, to complete any one of its delivery movements which may have been halted by untoward resistance.

4. The combination with an oven, a movable conveyor located therein, and a delivery-surface positioned adjacent to the conveyor; of a loading-mechanism for delivering articles from the said surface to the conveyor, comprising a reciprocating pusher-bar, a timer therefor, an electric motor for driving the said timer, and an electric switch interposed in the circuit of the said motor and brought into operation by variations in the resistance offered by the articles to the delivery movement of the bar for starting and stopping the said motor and timer; whereby the pusher-bar is compelled, before it can be retracted, to complete any one of its delivery movements which may have been halted by untoward resistance.

5. The combination with an oven, a movable conveyor located therein, and a delivery-surface positioned adjacent to the conveyor; of a loading-mechanism for delivering articles from the said surface to the conveyor, comprising a reciprocating pusher-bar, a timer-cam therefor, an electric motor for driving the said timer-cam, and an electric switch interposed in the circuit of the said motor and brought into operation by variations in the resistance offered by the articles to the delivery movement of the bar for start-

ing and stopping the said motor and timer-cam; whereby the pusher-bar is compelled, before it can be retracted, to complete any one of its delivery movements which may have been halted by untoward resistance.

6. The combination with an oven, a movable conveyor located therein, and a delivery-surface positioned adjacent to the conveyor; of a loading-mechanism for delivering articles from the said surface to the conveyor, comprising a reciprocating pusher-bar, a timer-cam therefor, an electric motor for driving the said timer-cam, means for connecting the said timer-cam and the said bar,

including two relatively-movable members, 15 a spring for holding them in their normal relative positions, a switch carried by one of the said members, and means carried by the other of the said members for actuating the said switch to break the circuit to the said motor; whereby the pusher-bar is compelled, before it can be retracted, to complete any one of its delivery movements which may have been halted by untoward resistance.

In testimony whereof, I have signed this 25 specification.

WALTER C. HUTH.
